UNITED STATES PATENT OFFICE.

JAMES DIXON, OF WHITWELL, TENNESSEE.

CAR-TIPPLE.

1,245,886.

Specification of Letters Patent.

Patented Nov. 6, 1917.

Application filed June 8, 1917. Serial No. 173,523.

To all whom it may concern:

Be it known that I, JAMES DIXON, a citizen of the United States, and a resident of Whitwell, in the county of Marion and State of Tennessee, have invented new and useful Improvements in Car-Tipples, of which the following is a specification.

My invention is an improvement in car tipples, and has for its object to provide mechanism of the character specified for dumping loaded cars, wherein a rotatable cylinder is provided, carrying holders for loaded and empty cars, and so arranged that a half rotation of the cylinder will turn the cars completely over to dump the load, and wherein the loaded cars are run down into the tipple and the empty cars are run down out of the tipple, giving a downward inclination in both directions.

20 A further object of the invention is to provide automatically operated mechanism for locking the cars in the holders and for releasing them when in delivering position, and wherein the delivery means is reversible to permit the cars to be delivered at either end of the tipple.

In the drawings:

Figure 1 is an end view of the improved tipple;

30 Fig. 2 is a side view;

Fig. 3 is a longitudinal section of one of the holders;

Fig. 4 is a section on the line 4—4 of Fig. 3, looking in the direction of the arrows adjacent to the line;

35 Fig. 5 is a section on the line 5—5 of Fig. 4;

Fig. 6 is a sectional view showing the reversing mechanism;

40 Fig. 7 is a bottom plan view of the holder;

Fig. 8 is a perspective view of the slide and the reversible tilting mechanism for the car;

Fig. 9 is a top plan view of a portion of Fig. 8, showing the holding dogs;

45 Fig. 10 is a perspective view of one end of the switch;

Fig. 11 is a diagrammatic view showing the arrangement of the tracks with respect 50 to the tipple.

In the present embodiment of the invention, a suitable shaft 1 is keyed in bearings 2 on a suitable supporting frame 3, and on this shaft are mounted disks 4, and 55 the said disks support two similar carriers

or holders 5 for the cars, the said holders being substantially cylindrical casings having openings 6 at their top for permitting the coal to be discharged when the holders are reversed.

60

The cylinder has at one end a gear ring 7 which is engaged by a pinion 8 on a counter-shaft 9 journaled in suitable supporting brackets 10, and the shaft has a gear wheel 11, which meshes with the pinion 65 12 on the shaft of a motor 13. When the motor is in operation, the cylinder will be turned, turning in the direction of the arrows in Fig. 1.

A gear wheel 14 is arranged concentric 70 with the shaft 1, but fixed, and the adjacent end of each holder 5 is provided with a gear ring 15 meshing with the gear ring 14. The holders are mounted to rotate in the disks 4, and it will be evident that when the 75 cylinder is rotated a half turn, each holder will be rotated a complete turn, moving the car from upright to dumping position and from dumping to upright position.

The improved tipple is arranged as shown 80 in Fig. 11, tracks 16, 16^a and 17, 17^a being provided for conducting the loaded cars to the tipple and the empty cars from the tipple, respectively, and the said tracks are arranged so that the cars may move toward 85 and from the tipple in either direction. A tiltable section of track 18 is arranged within each holder, and each of the said track sections is provided with oppositely extending journal pins 19, which are journaled in 90 bearings 20 in the holder. When the tiltable track section is tilted in one direction, the cars will run out at one end of the tipple, while when the track section is tilted in the opposite direction the cars will run out at 95 the opposite end.

Each of the track sections is provided near each end with wheels or rollers 21, and these wheels or rollers engage and rest upon a movable tilter 22. This tilter is mounted 100 to slide longitudinally of the holder 5, and each end of the tilter has a species of cam 23, the said cams being inclined as shown, and the wheels or rollers 21 of the tiltable track section rest upon the inclined surfaces. 105 The tilter is shifted by a shifter 24 which is secured to the tilter, as indicated at 25, a spacing plate 26 being arranged between the tilter and the shifter. The shifter has a wheel 27 journaled in each end thereof, 110

and these wheels engage tracks 28 which are secured to the disks 4.

The holders 5 have openings 29 in their bottoms, and the spacing plates 26 are in these openings, the arrangement being such that the shifter 24 is outside of the holder, while the tilter 22 is within the holder. These tracks 28 have cut away portions 30.

A switch lever 31 is pivotally mounted, as indicated at 32, between the cut away portions of the track, and each end of the lever is provided with a cam or switch head 33, shown more particularly in Fig. 10, and adapted to fill the cut away portions 30 of the tracks. These cams are similar, and the lever is angular, so that when one cam is in engagement with a cut away portion of the track, the other cam will be depressed below the said cut away portion, leaving the said cut away portion open. The wheels 27 of the shifter move in contact with the tracks, and it will be evident that when the shifter strikes the cut away portions it will be moved longitudinally in one direction, dependent upon the position of the lever 31.

A handle 34 is connected with one of the cams, for swinging the lever, so that the shifter may be moved in either direction. When the shifter is moved as indicated in Fig. 6, the tilter will be moved therewith, and will tilt the car, one of the wheels 21 rolling down the incline or cam 23, while the other wheel rolls up to the high part of the said cam. When the car is released, it will be evident that it will roll out of the holder and down the track.

Mechanism is provided for automatically locking the car as it moves on to the tilting track section and for releasing the same after it has been dumped. The said mechanism comprises a pin 35 which is held in spaced relation below the bottom of the car and at the center thereof by substantially A-shaped brackets 36, the bases of the brackets being secured to the car, with the apices below said car, and the said apices support the pin. This pin is adapted to engage beneath one of the arms of a T-shaped anchor 37 which is connected with the tilting track section in line with the journal pins 19 and between the same. As the car comes on to the tilting track section from either direction the pin 35 will move beneath the adjacent arm of the anchor, and locking means are provided for locking the pin beneath the anchor at either side thereof. Each of the said means comprises a latch plate 38, each plate being pivoted at 39 to the tilting track section in a slot in the said section, and each plate has a rounded opening 40 for receiving the pin, and a tail 41 for engaging a dog 42 in the shifter to hold the plate in substantially vertical position, with the pin 35 in the opening 40. It will be evident from an in-

spection of Fig. 3 that as long as the latch plate is held in this position the pin cannot become disengaged. Normally, the latch plates hold the position at the right of the anchor in Fig. 3, the latch plates being weighted to assume this position when released. When a car is run on to the track section, with the latch plate in the position shown at the right of the anchor in Fig. 3, the pin will move into the opening 40 and will swing the latch plate upwardly into the position at the left of the anchor. The dogs 42 are pivoted in an opening 43 in the tilter on a common pivot indicated at 44, and they are normally pressed upwardly into engaging position by coil springs 45 arranged beneath the dogs.

Referring to Fig. 3, it will be seen that as long as the tilter is in the full line position of the said figure the operative latch plate 85 will be held in engaging position by the adjacent dog. When however, the tilter is shifted into the dotted line position of Fig. 3 the latch plate will be released by the dog, and gravity will cause the car to run off the 90 tiltable track section, which will be tilted by the shifting of the tilter.

In operation, the loaded cars 46 are run down the tracks 16 and 16^a into that holder which has its tiltable track section in register with the tracks 16 and 16^a. The motor will rotate the cylinder, moving the loaded car from the position at the right and bottom of Fig. 1 to the left and top of said figure, and turning the car completely over 100 during the movement to dump the load. As the car comes into the last named position, the shifter will be shifted to shift the tilter and release the latch plate, and the car will roll out at one end of the tipple, depending upon the position of the switch lever 31. Locking pawls 47 are pivoted to the frame-work 3, and these pawls engage notches 48 in the adjacent disk to prevent reverse movement of the cylinder. These pawls hold the cylinder in locked position until the empty car is run off and the loaded car is run in. A clutch 49 is provided for connecting the counter-shaft with the pinion 8, and the said clutch is operated by a 115 lever 50. But little power is required to turn the cylinder, since the weight of the empty holder assists in lifting the loaded car, and the loaded car is dumped after a quarter turn.

It will be noted that the shaft 1 is keyed to the support 3 and the bearing, while the gear wheel 14 is secured to the shaft, the shaft and the gear wheel being stationary with the supporting frame. The pawls 47^a are keyed to a shaft 51 journaled in the supports 3, and they are operated by the tipple operator by means of a lever 52 pivoted to an arc shaped support 53 and connected to a depending arm 54 on the shaft by means 130

of a link 55. The pawls 47 do not require to be operated, being spring-pressed into place.

I claim:

- 5 1. A car tipple comprising a shaft, a cylinder on the shaft, means for rotating the cylinder, holders for the cars of substantially cylindrical form and open at their tops to permit the cars to discharge, said holders being at diametrically opposite points, a track for the cars in each holder, each track being supported between its ends to tilt in either direction, means for holding the track level, means for locking the cars to the holders, a common means for releasing the locking means and tilting the track controlled by the rotation of the holders, and means for rotating the holders a complete rotation during each half rotation of the cylinder.

10 2. A car tipple comprising a cylinder mounted to rotate on its axis, means for rotating the cylinder, a plurality of holders for the cars mounted to rotate in the cylinder, said holders being at diametrically opposite points, a track in each holder mounted to tilt in either direction, means for holding the track level, means for locking the cars to the holders, a common means for releasing the locking means and tilting the track controlled by the rotation of the holders, and means for rotating each holder a complete rotation during each half rotation of the cylinder.

15 3. A car tipple comprising a cylinder mounted to rotate on its axis, means for rotating the cylinder, a plurality of holders for the cars mounted to rotate in the cylinder, said holders being at diametrically opposite points, a track in each holder mounted to tilt in either direction, means for holding the track level, means for locking the cars to the holders, and a common means for releasing the locking means and tilting the track controlled by the rotation of the holders.

20 4. A car tipple comprising a cylinder mounted to rotate on its axis, means for rotating the cylinder, a plurality of holders for the cars mounted to rotate in the cylinder, said holders being at diametrically opposite points, a track in each holder mounted to tilt in either direction, means for holding the track level, means for locking the cars to the holders, and a common means for releasing the locking means and tilting the track controlled by the rotation of the cylinder.

25 5. A car tipple comprising a cylinder mounted to rotate on its axis, means for rotating the cylinder, a plurality of holders for the cars mounted to rotate in the cylinder, said holders being at diametrically opposite points, a track in each holder mounted to tilt in either direction, means for holding the track level, means for locking the cars to the holders, and a common means for releasing the locking means and tilting the track controlled by the rotation of the holders.

30 6. A car tipple comprising a plurality of holders, a rotatable support in which the holders are mounted, means for rotating the support, means for rotating the holders a complete rotation during each half rotation of the support, means for locking the cars to the holders, means controlled by the rotation of the holders for releasing the locking means when the cars have been dumped, a track in each holder for supporting a car and mounted to tilt in either direction, and means in connection with the locking means for tilting the track when the locking means is released.

35 7. A car tipple comprising a plurality of holders, a rotatable support in which the holders are mounted, means for rotating the support, means for rotating the holders a complete rotation during each half rotation of the support, means for locking the cars to the holders, and means controlled by the rotation of the holders for releasing the locking means when the cars have been dumped.

40 8. A car tipple comprising a plurality of holders, a rotatable support in which the holders are mounted, means for rotating the support, and means controlled by the rotation of the support for rotating the holders a complete rotation during each half rotation of the support.

45 9. A car tipple comprising a plurality of holders, a rotatable support for the holders, means for rotating the support, means for rotating the holders a complete rotation during each half rotation of the support, a tilting track for the cars in each holder, means for tilting the track, means for locking the cars to the holders, and a common means for releasing the locking means and tilting the track controlled by the rotation of the holders.

50 10. A car tipple comprising a plurality of holders, a rotatable support for the holders, means for rotating the support, means for rotating the holders a complete rotation during each half rotation of the support, means for tilting the cars to discharge them from the holder, means for locking the cars to the holders, and a common means for releasing the locking means and operating the tilting means.

55 11. A plurality of means for holding cars and revoluble about a common axis and arranged on opposite sides of the axis, means

for revolving the holders, and means for rotating the holders a complete turn during each half revolution, means within the holders for tilting the cars in either direction to cause them to run out of the holders and controlled by the movement of the holders.

12. A plurality of means for holding cars and revolute about a common axis and arranged on opposite sides of the axis, means for revolving the holders, and means for rotating the holders a complete turn during each half revolution, means within the holders for tilting the cars to cause them to run out of the holders and controlled by the movement of the holders.

13. A plurality of means for holding cars

and revolute about a common axis and arranged on opposite sides of the axis, means for revolving the holders, and means controlled by the revolving of the holders for 20 rotating the holders a complete turn during each half revolution.

14. A means for holding cars revolute about an axis parallel with the long axis of the car, and means controlled by the revolving of the holder for rotating the holder while it is revolving about an axis. 25
